UNITED STATES PATENT OFFICE.

RICHARD K. HOHmann, OF PERU, INDIANA, ASSIGNOR TO HOHmann SEWING MACHINE COMPANY, OF PERU, INDIANA, A CORPORATION OF INDIANA.

SEWING-MACHINE MECHANISM.

Application filed August 7, 1923. Serial No. 656,185.

The general object of my present invention is to provide an improved loop forming mechanism for rotary hook sewing machines, especially adapted for use in a high speed 5 sewing machine in which the thread bobbin employed is several times larger than those employed in the high speed sewing machines now in general use.

The various features of novelty which 10 characterize my invention are pointed out with particularity in the claims annexed to and forming a part of this specification; for a better understanding of the invention however, its advantages and specific objects attained with its use, reference should be made 15 to the accompanying drawings and descriptive matter in which I have illustrated and described a preferred embodiment of my invention.

20 Of the drawings:

Fig. 1 is an end elevation of a sewing machine head;

Fig. 2 is an end elevation of a portion of the apparatus shown in Fig. 1, taken on a 25 larger scale and with parts broken away and in section;

Fig. 3 is a section on the line 3—3 of Fig. 2; and

Fig. 4 is a section of the hook ring taken 30 on the line 4—4 of Fig. 3; and Fig. 5 is a partial section taken on the line 5—5 of Fig. 2.

In the drawings, A represents the head of a sewing machine provided with the usual 35 base or bed A'. Mounted in the head A, are the rotary take-up mechanism B, the needle bar C and the presser bar D. Beneath the bed A' is located the rotary hook ring E, which is carried by a shaft F and makes two revolutions for each complete reciprocation of 40 the needle bar C.

The hook ring E, as shown, is formed in two parts i. e. an annular rim, or body e, and a spider member e'. At its front end, the 45 ring body e is provided with an internal flange E', which with a rim portion of the spider member e', and the inner surface of the ring body e forms a bearing groove E² for the shuttle G. The hook ring E is cut 50 away at one portion of its periphery to form the loop taking hook E³, and the usual notch E⁴ in front of the hook E³. A thread deflector element E⁵ is secured to the hook ring 55 and extends across the notch E⁴. The hook ring is provided with a thread guard finger

E⁶ the form and purpose of which is hereinafter described.

The shuttle G is formed with a peripheral bearing rim G' which is received in the ring bearing groove E² and the shuttle is also provided along a portion of its periphery with a radial flange G² projecting in front of the hook ring and formed with shoulders G³ and G⁴ which cooperate in the usual manner with a stop lug A² attached to the bed A' of the machine and holding the shuttle against 60 rotative movement other than that required to permit the thread to pass between the shuttle and the stop A² in each loop forming operation. Detachably mounted in the shuttle G is a bobbin casing element H in which the bobbin H' is held, and which unites with the shuttle member G to form a complete 65 bobbin housing forming element about which the thread loop is passed in each stitch forming operation.

The thread guard finger E⁶ carried by the hook ring, in the particular construction illustrated, is in the form of an integral portion of the hook ring spider element e' which projects to the rear from the front end of the notch having reference to the direction of rotation of the hook ring E which is counter-clockwise. The finger E⁶ which is tapered, lies back of the shuttle bearing rim G', and the point of the finger E⁶ moves in 70 close proximity to the rear side of the bearing rim along a circular path, the diameter of which is appreciably smaller than the diameter of the bearing rim as is clearly shown 75 in the drawings. The outer side of the finger E⁶ slopes outwardly from the point of the finger toward the periphery of the bearing rim. The purpose of the guard finger E⁶ is to engage the thread loop and hold it 80 out of contact with the shuttle bearing rim G', when the thread loop is pulled off the hook E³ in the final portion of each stitch forming operation, thereby avoiding all possibility of the thread being drawn into the 85 joint between the bearing rim G' and the rear and outer walls of the bearing groove E². The manner in which the thread is engaged and protected by the finger E⁶ will 90 be apparent to those skilled in the art from 95 the showing in Figs. 2 and 3, wherein I indicate the front limb, and L' the rear limb 100 of the thread loop.

As before stated, the invention is of special 105 utility in the case of a high speed big bob- 110

bin sewing machine, employing a rotary take-up mechanism, such as the machine illustrated which is designed to make about four thousand stitches a minute and to receive bobbin H' holding about 265 yards of No. 60 cotton thread. In a machine of this sort the relatively large take-up movement required can best be obtained with a rotary take-up mechanism which draws up the front limb I of the loop very rapidly after the loop is cast off the hook E³. With the described arrangement, the point of the finger E⁶ is angularly in advance of the point of the hook E³ and the thread loop is drawn away from the finger E⁶ and above the path of the rotary hook before the latter comes into loop taking position. The tendency of the thread to jam between the shuttle bearing rim G' and the walls of the bearing groove E² in the ring E, which it is the primary purpose of the invention to prevent, might be substantially eliminated by elongating the notch E⁴, so that the front end of the notch would be farther away from the point of the hook E³, but this involves a decreased amount of bearing surface between the hook ring E, and the shuttle bearing rim G', which, as those skilled in the art known, must also be notched angularly in advance of the shoulder G⁴, and such decrease in bearing surface is objectionable as it tends to looseness in the shuttle mounting with resulting undesirable lost motion, and play of the shuttle in its bearing.

While in accordance with the provisions of the statutes I have illustrated and described the best form of my invention now known to me, it will be apparent to those skilled in the art that changes may be made in the form of the apparatus disclosed without departing from the spirit of my invention as set forth in the appended claims, and that certain features of my invention may sometimes be used to advantage without a corresponding use of other features.

Having now described my invention, what I claim as new, and desire to secure by Letters Patent, is;

1. In a rotary hook sewing machine comprising a rotating hook member formed with an internal bearing groove, and with a loop taking hook and with a peripheral notch alongside and in front of said hook, and a non rotating shuttle formed with a peripheral bearing rim received in said groove, the improvement which consists in

a thread guard finger carried by said hook member and projecting rearwardly from the front end of the notch, having reference to 60 the direction of rotation of the hook member, and terminating angularly in advance of the point of the loop taking hook, in a point moving in close proximity to the rear side of said bearing rim along a circular path of smaller diameter than said bearing rim.

2. In a rotary hook sewing machine comprising a rotating hook member formed with an internal bearing groove, and with a loop taking hook and with a peripheral notch alongside and in front of said hook, and a non rotating shuttle formed with a peripheral bearing rim received in said groove, the improvement which consists in a thread 75 guard finger carried by said hook member and projecting rearwardly from the front end of the notch, having reference to the direction of rotation of the hook member, and terminating angular in advance of the point 80 of the loop taking hook, in a point moving in close proximity to the rear side of said bearing rim along a circular path of smaller diameter than said bearing rim, the outer side of said finger sloping outwardly from 85 the point thereof toward the periphery of said bearing rim.

3. In a high speed big bobbin rotary hook sewing machine comprising a rotating hook member formed with an internal bearing 90 groove and with a loop taking hook and with a peripheral notch alongside and in front of said hook and a non rotating shuttle formed with a peripheral bearing rim received in said groove and a rotary take 95 up mechanism adapted to draw the thread loop above said hook member before the latter completes a loop drawing revolution, the improvement which consists in a thread guard finger carried by said hook member and projecting rearwardly from the front 100 end of the notch having reference to the direction of rotation of the hook member and terminating angularly in advance of the point of the loop taking hook and comprising an operative portion at the rear of said groove and less remote from the axis of the hook member than the bottom of said groove.

Signed at New York city in the county 110 of New York and State of New York this 3 day of August A. D. 1923.

RICHARD K. HOHMANN.
